SELF-PILOTED ROTARY DRILL BIT

Orville Phipps, Adams County, near Denver, Colo.

Application March 19, 1951, Serial No. 216,308

5 Claims. (Cl. 255—61)

1

This invention relates to bits rotatable with and as the free end termination of a drill string to develop bores in and through earth strata, and has as an object to provide an improved such bit characterized by high penetrative efficiency.

A further object of the invention is to provide an improved removable and replaceable drill bit of multi-wing, "stepped" type operatively conservative of power and time.

A further object of the invention is to provide an improved rotary drill bit operable for the simultaneous development of coaxial cuts of progressively greater radii determinative of a straight bore of the desired diameter.

A further object of the invention is to provide a "stepped" type rotary drill bit that is facile and economical of production in any desired range of sizes, adaptable at the time of production to variations suited to particular operating problems and conditions, susceptible of convenient rehabilitation in the field, and durable throughout a long life of practical use.

With the foregoing and other objects in view, my invention consists in the construction, arrangement, and combination of elements herein-after set forth, pointed out in my claims, and illustrated by the accompanying drawing, in which—

Figure 1 is an end elevation of a typical embodiment of the invention. Figure 2 is a side elevation of the improvement according to Figure 1. Figure 3 is an end view of the illustrated embodiment, partly in section, taken substantially on the indicated line 3—3 of Figure 2. Figure 4 is a longitudinal section through the illustrated embodiment taken substantially on the indicated line 4—4 of Figure 1.

In the construction of the improved bit, as shown, the bit body, formed of tractable metal, preferably by forging, is constituted with a right-cylindrical base or butt portion 10, an integral, frusto-conical portion 11 coaxial with the base portion 10 and tapering thence to a working or free end of reduced diameter, and an integral, coaxial boss 12 of relatively reduced diameter outstanding from the base 10 end remote from the portion 11 in a working of its exterior surface, as by means of threads, adapting said boss to function as means for removably and replaceably associating the bit body with, as a coaxial free end extension of, and for rotation about its axis by a conventional power-rotatable drill string with the reduced end or tip of the body portion 11 directed away from the said string; it being desirable, in accord with customary practice, that the boss 12 operate to abut the end of the drill string against

2

the end of the base portion 10 in a smooth, co-incident registration of the base and drill string exterior surfaces. A straight, axial bore 13 of maximum practical diameter longitudinally intersects the bit body and opens through the opposite ends thereof to constitute a passage for the flow of cooling and scavenging fluid from and as conventionally supplied through the associated drill string, and the end of said bore opening through the reduced end of the portion 11 is internally threaded for purposes which will hereinafter appear.

Characteristic of the improvement, and giving effect to certain principles of the invention, a plurality of like wings 14 is formed integrally with and to standout in a uniform angular spacing laterally from the bit body in a number, two, three, four, or more, and particular relation with the bit body suited to given operating conditions; 15 three such wings being shown in the drawings. Each of the wings 14 has a smooth, plane face 15 leading in the direction of bit rotation and radial of the bit body at the lesser or free end of the latter remote from the boss 12, said face 15 being 20 inclined at any appropriate small angle selected at the time of the bit manufacture relative to a plane through the bit axis to dispose the end of the wing adjacent the boss 12 in rotationally trailing relation with the wing end remote from said boss, thereby to impress a positive operational "rake" on the bit wings, the trailing face of each wing 14 is preferably tangential with the frusto-conical bit body portion 11 exterior surface, and the edge, or free side margin, of each wing 14 is stepped, in three or more stages, from 25 a minimum projection radially and outwardly of the bit body at the lesser end of the portion 11 to a maximum radial and outward projection, determinative of ultimate bore diameter, adjacent the emergence of said portion 11 with the base 10, 30 whence the said wing edge inclines inwardly and toward the boss 12 to merge into said base; the free edge margin of each of the so-constituted wing steps being parallel to the bit body axis.

45 The tractable nature of the metal from which the bit elements 10, 11, 12, and 14 are comprised enhances the facility and economy of bit manufacture but is ill-suited to withstand the abrasive and wear effects of bit operation, hence 50 the step corners and adjacent leading face areas of the wings, being the cutting elements of the assembly, are armored and protected by blocks 16 of suitable hard, tough, abrasion-resistant, alloy material, such as tungsten-carbide, recessed and secured, as by brazing or welding, in

and in flush relation with each wing leading face in an end-overlapped, stepped interrelation appropriate to register and align outer side margins and exposed end corners of said blocks with the corresponding margins and end corners of the wing steps; said blocks 16 being generally rectangular in plan and section, of a size in plan to longitudinally interengage and laterally overlap, and of an adequate stress-resistant thickness less than the wing thickness at their mountings thereon, whereby to provide a backing of tractable material in supporting relation with each block. Inner margins and the trailing faces of the blocks 16 are closely conformed with the corresponding recess elements and are firmly and permanently adhered thereto by known and readily-available techniques. With the blocks 16 mounted in the arrangement and relationships shown and described, the side margins of the blocks are ground into smooth mergence with the adjacent wing step margins, exposed end corners of said blocks and their backing step material are laterally beveled as may be desired, and said corners are ground to advance leading edges of said corners longitudinally of the bit assembly beyond their trailing edges in a "bite" of appropriate or desired pitch; maintenance of the block working side margins and end corners in efficient functioning condition being a simple grinding operation convenient of performance in the field and of repetition until the block width is substantially exhausted.

In the angle between adjacent wings 14, and hence in immediate leading relation with the armored working face of each wing, holes 17 are formed in any desired number, two or more, through the body portion 11 to communicate with the bore 13 and provide fluid outflow from said bore to and across the block 16 faces, with cooling and scavenging effect thereon; said holes preferably being appropriately inclined relative to the bore axis to facilitate and suitably direct such outflow.

Completing the drill bit assembly for practical operation, a separate pilot bit unit is removably and replaceably associated with and to project axially from the end of the bit body remote from the boss 12, said pilot bit unit being formed on and mounted by means of an externally-threaded, cylindrical stem 18 cooperable with the internal threads at the outer end of the bore 13 in obstructing relation with said bore end. Formed integrally with the stem 18, a head 19 of tractable material is worked to provide a pair of like, opposingly-complementary fingers 20 outstanding axially from and radially overhanging the stem 18 in an outer marginal orbit covering the lesser end of the body portion 11, said fingers 20 having opposingly-faced, straight inner margins registered in a common diametric plane through the stem 18 axis and opposingly-faced, plane faces at the opposite sides of said diametric plane similarly spaced from a second diametric plane perpendicular to said first plane, whereby to define a slot extending diametrically of the head 19 between said fingers and opening outwardly axially thereof. The fingers 20 are arranged to dispose their plane faces in the direction of bit rotation, and a block 21 of alloy material, conveniently the same as that from which the blocks 16 are formed, is edge-seated in and to fill the diametric slot between said fingers and to extend at each end beyond the side margins thereof with its free, or outer, edge disposed diametrically and projected axially relative to the head 19. Thus, the side

margins, exposed faces, and end edges of the fingers 20 are armored and protected by the block 21 alloy material which functions as the advanced cutting element of the assembly during bit rotation and develops a pilot bore of small diameter effective to guide the bit in its enlargement of the pilot bore and to facilitate the work of the blocks 16, the working margins of said block 21, both side and end, being ground to merge with their backing material in such "bite" inclination as may be appropriate. Exterior corners and adjacent surface areas of the fingers 20 immediately beneath the outer ends of the block 21 undesirably abrade and wear away during operation of the bit when constituted solely from the tractable material of the head 19, hence it is expedient to armor and protect said corners by means of strips 21' of wear-resistant alloy material recess-seated and secured in the outer end corners of the finger 20 plane faces to close between the base of each finger and the inner margin of the corresponding block 21 end. A bore 22 axially of the stem 18 is branched within the head 19 to open through the base of each finger 20 adjacent the leading face area of the block 21, thereby to provide flow of cooling and scavenging fluid across the block working faces and about the block working edges.

It is to be noted that the arrangement of wings 14 and pilot bit fingers 20 results in an unusually large space through which fluid carrying cuttings may uprise with efficient scavenging effect to obviate any clogging or sticking of the drill due to poor scavenging; that the provision of the alloy blocks as the sole cutting elements of the bit in an arrangement permitting rehabilitation of their cutting edges in the field conduces to a long and operatively efficient bit life; and that the stepped relationship of the block 21 and 16 side margins is productive of a progressive bore enlargement conducive to straight bore development and low power requirements.

Since changes, variations, and modifications in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A bit of the character described comprising a body of tractable metal formed with a cylindrical base portion and a coaxial frusto-conical portion tapering from said base portion to a free working end of reduced diameter, means on the free end of said base portion removably and replaceably engageable with and to mount said body as a simultaneously-rotatable terminal extension on a drill string, integral wings outstanding laterally from and in a uniformity of angular spacing about said body and a mergence of their appropriate ends into the body base portion, plane surfaces approximately radial of the body at a slight longitudinal inclination to the body axis defining the wing faces leading in the direction of body rotation with their ends adjacent the body free end advanced in the direction of rotation relative to their opposite ends, angular steps similarly interrupting free side margins of said wings to define successive annular cutting zones perpendicular to the body axis and of progressively greater diameters away from the body free end, blocks of abrasive-resistant alloy material recess-seated and secured in the leading face

area of each wing step in marginal registration therewith, means for the circulation of fluid through said body and outwardly thereof between adjacent wings, and a pilot bit removably and replaceably outstanding coaxially from the free end of said body.

2. The organization according to claim 1, wherein the wing surfaces trailing in the direction of body rotation merge into and tangentially with the body surface for the development of a wing root buttressed against the stresses incident to bit operation.

3. The organization according to claim 1, wherein the said angular steps are right angular with their side margins paralleling the body axis 15 and their end margins in planes perpendicular to the said axis.

4. The organization according to claim 1, wherein the blocks of alloy material are generally rectangular in a relative size and mounted inter- 20 relation to overlap the outer side margin of a lesser diameter step block on the end margin of the next greater diameter step block and outwardly beyond the inner side margin of said latter block.

5. The organization according to claim 1,

wherein said pilot bit is constituted with a body of tractable metal, is furnished with a block of alloy material slot-seated diametrically of the body free end in an axially-directed, cutting exposure of its outer edge and a projection of its ends effective to overlap the cutting orbit of the adjacent wing alloy blocks, and is bored for the circulation of fluid from the associated bit body across and in advance of its alloy block working elements leading in the direction of bit rotation.
